(57) CLAIM

The ornamental design for a furniture top, as shown and described.

DESCRIPTION

FIG. 1 is a perspective view from above of a furniture top showing my new design;

FIG. 2 is a front view of the furniture top of FIG. 1;

FIG. 3 is a left side view of the furniture top of FIG. 1;

FIG. 4 is a right side view of the furniture top of FIG. 1;

FIG. 5 is a rear view of the furniture top of FIG. 1;

FIG. 6 is a top view of the furniture top of FIG. 1; and,

FIG. 7 is a bottom view of the furniture top of FIG. 1.

In the drawings, the broken lines illustrate the environment in which the furniture top is used and forms no part of the claimed design.

The furniture top may be used for a stool, chair or table.
